UNITED STATES PATENT OFFICE.

JAMES A. STREET, OF DETROIT, MICHIGAN, ASSIGNOR OF ONE-THIRD TO HUGO C. ZEITZ, OF CLARKSBURG, WEST VIRGINIA, AND ONE-THIRD TO FRANKLIN O. PRUSIA, OF DETROIT, MICHIGAN.

HEADLIGHT.

Application filed August 3, 1925. Serial No. 47,759.

My invention relates to improvements in headlights.

The object is to produce a headlight particularly intended for use on motor vehicles, of attractive appearance and rigid, durable construction, with mechanism under control of the driver whereby the light rays may be directed at the desired angle and so as not to interfere with the vision of the driver 10 of an approaching vehicle. I accomplish this object not by swinging the entire headlight assembly but by providing the headlight with a reflector so supported within the casing as to be capable of being tilted 15 both vertically and horizontally and held at adjusted angular positions.

An object of importance is the provision in a headlight of the character described of angularly-arranged guiding supports carried by the headlight casing and correspondingly angularly arranged supporting bands about the reflector, which bands are mounted within the guides in the casing to travel therethrough to support the reflector for 25 tilting movement.

Meritorious features consist in the employment of supporting mechanism adapted to hold the reflector at any position to which it has been adjusted without rattle and to 30 swing the reflector to adjusted angular positions without play of the parts producing undesirable noise.

Other important elements reside in the employment of guides for the supporting bands, consisting of guiding members disposed on opposite sides of the reflector and held under spring tension against the bands to prevent rattle of the moving parts as the bands travel through the guides together 40 with the employment of tension springs engaging the bands to hold the reflector at the limit of its movement in one direction as provided for by each band.

The above objects and important advantages together with others of considerable merit will more fully appear from the following specification, appended claims and accompanying drawings, in which:

Figure 1 is a front elevation of my improved headlight.

Fig. 2 is a horizontal sectional view taken on line 2—2 of Fig. 1.

Fig. 3 is a vertical sectional view taken on line 3—3 of Fig. 1.

Fig. 4 is a sectional view taken on line 55 4—4 of Fig. 3.

Fig. 5 is a perspective of the headlight from the rear with the casing broken away.

Fig. 6 is a perspective of one of the supporting guide brackets.

I provide a headlight having a rigidly supporting casing 10 within which is mounted a reflector 12. The casing is provided with the usual headlight lens 14 held in position in a manner well known and is supported by a hollow bracket 16 through which extends the electrical connection 18 that leads to the light bulb 20 removably mounted within a socket 22 carried by the reflector 12. This reflector is supported within the 65 casing for tilting movement both horizontally and vertically and the connecting wire 18 is of such length as to permit this tilting movement. The reflector consists of a bowl-shaped member of suitable material 75 supported to permit of the swinging movement above described as follows:

The casing is provided with angularly arranged guiding supports. I have shown each guiding support as comprising two 80 guide members positioned on opposite sides of the reflector in substantially the same plane, and each guiding member consists of a plurality of rollers 24 and 26. I have shown two rollers 24 carried by a suitable 85 bracket 28 and a single roller 26 held by springs 30 to a seat 32 on the bracket 28 and toward the rollers 24. Each guide member is of the same construction.

The reflector is provided with two bands 90 34 extending about the reflector, which bands are arranged angularly corresponding to the angular arrangement of the guides carried by the casing. Each band is here shown as consisting of a piece of flat metal turned under at the ends as at 36 and pivoted by a pivot pin 38 to a support 40 on the reflector. These bands cross each other and each band is mounted in a guide for travel therethrough to support the reflector for swinging movement. It will be seen that the rollers 26 which are held by the springs 30 hold the bands 34 against the rollers 24.

The two bands just described which are disposed substantially at right angles to each other are pivoted to the reflector in substantially the same plane and so support the reflector as to permit of it being tilted both in

the vertical and in the horizontal direction and of its being tilted in either direction while held tilted in the direction of its other permitted movement.

5 A spring 42 is connected at 44 to each band at a point sufficiently remote from where the bands cross each other so as not to interfere with the movement of the bands and is fastened at the opposite end to a fixed point 10 such as 46 within the casing. This spring under normal conditions serves to hold the reflector to the full extent of its tilting movement in one direction, as in Fig. 2. The spring on the other band will, of course, 15 hold the reflector to the full extent of its tilting movement as permitted by such other band. The springs, therefore, unless restrained, would hold the reflector tilted to the full extent of its vertical movement in 20 one direction and to the full extent of its horizontal movement in one direction.

I provide means to actuate each band slidably through its supporting guide, which means may be of any suitable character and 25 is here shown as comprising a flexible connection 48 connected with the reflector at 50 whereby the band may be moved against the tension of its spring 42 to the full extent of its movement in a direction counter the tension of the spring.

In Figs. 3 and 5 the reflector is shown in full lines at an intermediate position. In Fig. 2 the reflector is shown in full lines as held completely to one side by the spring 35 42 while the intermediate position of the reflector and its full swinging movement in the opposite direction is indicated in dotted lines.

What I claim is:

40 1. In a headlight, a casing member, a reflector member disposed within the casing member, relatively angularly arranged bands secured to one member, correspondingly relatively angularly arranged guides carried by 45 the other member, said bands mounted within said guides to travel therethrough in angular directions with respect to each other to permit tilting of the reflector within the casing in relatively angularly disposed directions.

50 2. In a headlight, a casing, angularly-arranged guides within the casing, a reflector, angularly-arranged bands about and pivoted to the reflector, said bands mounted within 55 the guides to travel therethrough to support the reflector for swinging movement, and means operatively connected therewith to cause the bands to travel through the guides to tilt the reflector.

60 3. In a headlight, a casing provided with two guides one arranged substantially at right angles to the other, a reflector provided with two correspondingly arranged bands mounted for traveling movement 65 within the guides, one band within one guide,

the other band within the other guide to support the reflector to swing as the bands are moved through the guides, each band being pivoted at its ends to the reflector, and means operatively connected with the reflector to cause the bands to travel through the guides to swing the reflector.

70 4. In a headlight, a casing provided with angularly-arranged supporting guides, a reflector in the casing provided with correspondingly-arranged supporting bands mounted within the guides to travel therethrough to support the reflector for swinging movement, each band pivoted to the reflector to permit it to swing therein, and 75 means operatively connected with each band to move it through the guides to tilt the reflector within the casing.

80 5. In a headlight, a casing, a reflector within the casing, a light bulb within the reflector, a set of guides within the casing disposed on opposite sides of the reflector in substantially the same plane, a second set of guides within the casing likewise disposed on opposite sides of the reflector in substantially the same plane and in a plane angularly disposed with respect to the plane of the first set of guides, two bands about the reflector arranged angularly with respect to each other and pivoted to the reflector, 90 one band mounted in one set of guides to travel therethrough, the other band mounted in the other set of guides to travel therethrough to support the reflector for swinging movement in the casing, and means operatively connected with the bands to move the same through the guides to swing the reflector therewith.

95 6. In a headlight, a casing, roller guides within the casing disposed in angular relationship with respect to each other, a reflector, angularly arranged bands about the reflector, said bands mounted within the guides to travel therethrough to support the reflector for swinging movement, and means 105 operatively connected with the reflector to tilt the same, causing the bands to travel through the guides.

110 7. In a headlight, in combination, a casing member, a reflector member, a curved band 115 extending about the one member, roller guides carried by the other member, said band extending through said guides so that a roller is disposed on each side of the band, and means holding one of said rollers yieldably against the band and toward the other roller.

120 8. In a headlight, in combination, a casing, angularly arranged guides within the casing, a reflector, angularly arranged bands about the reflector and pivoted thereto, said bands mounted within the guides to travel therethrough to support the reflector for tilting movement, and a spring engaging 125 each band to hold it to the full extent of its 130

permitted movement through its guide, and means operatively engaging the bands to cause them to travel through the guides against the tension of said springs.

5 9. In a headlight, the combination of a casing member, a reflector member, a curved band extending about one member spaced from the surface thereof, guides carried by the other member, said band mounted within 10 said guides to travel therethrough to support the reflector for tilting movement within the casing, and means operatively engaging the reflector to tilt the same.

10. The invention as characterized in 15 claim 2, wherein each band is pivoted at each end to the reflector and one band passes over the other and the guides consist of rollers engaging the bands on opposite sides, one roller of each pair being held under spring 20 tension toward its co-operating roller in the pair.

11. In a headlight, a casing, a reflector within the casing, angularly-supported guides carried by the casing, each guide consisting of guiding supports arranged within the casing in substantially the same plane and on opposite sides of the reflector, said reflector provided with correspondingly arranged bands extending thereabout mounted within the guides for guided travel therethrough to support the reflector for swinging movement, each end of each band pivoted to the reflector such a distance from the adjacent guide as to permit the reflector to be 25 swung through a substantial arc in the direction of travel of the band through the guide.

12. The invention as characterized in claim 2, wherein each band is held under

spring tension to the full extent of its swinging movement in such direction.

13. In a headlight, a casing provided with angularly-arranged supporting guides, a reflector within the casing provided with correspondingly arranged supporting bands mounted within the guides to travel therethrough to support the reflector for swinging movement, each band pivoted to the reflector to permit it to swing therethrough, a spring connecting each band with the casing to hold the band in a given direction, and means engaging each band whereby it may be moved against the tension of its retaining spring to swing the reflector.

14. In a headlight, a casing, a bowl-shaped reflector carried within the casing, a light bulb carried within the reflector, angularly-disposed supporting guides carried by the casing, each guide comprising guiding members positioned on opposite sides of the casing in substantially the same plane, two angularly-disposed supporting bands extending about the reflector bowl and crossing each other, said bands mounted within the supporting guides for guided travel therethrough to support the reflector for swinging movement in the casing, retaining means engaging each band to hold it yieldably in one direction to the limit of its movement in such direction, and means operatively engaging each band to move the same through the casing to swing the reflector against the tension of said retaining means.

In testimony whereof, I sign this specification.

JAMES A. STREET.
